SPRING TENSION COVER FOR A DUAL-UNIT FOOD MOLD

Richard A. Hawley, Oakland, and Harold B. Hanson, San
Leandro, Calif., assignors to Meat Packers Equipment
Co., Oakland, Calif., a corporation of California

Filed June 17, 1963, Ser. No. 75,383

Term of patent 14 years

(Cl. D58—26)

FIG. 1.

FIG. 3.

FIG. 2.

FIG. 4.

FIG. 5.

FIG. 6.

FIG. 1 is a perspective view of a spring tension cover for a dual-unit food mold showing our new design; the broken line showing of a food mold being for purposes of illustration only.

FIG. 2 is an enlarged perspective view of the spring tension cover for a dual-unit food mold.

FIG. 3 is an end elevational view thereof.

FIG. 4 is a top plan view.

FIG. 5 is a side elevational view.

FIG. 6 is a bottom plan view.

We claim:
The ornamental design for a spring tension cover for a dual-unit food mold, as shown and described.
